Des. 196,430
Patented Oct. 1, 1963

196,430

ROCKING SEAT

Robert K. Andre, 611 Alhambra Circle, and Robert V. Edwards, 1240 San Remo Ave., both of Coral Gables, Fla.

Filed Feb. 14, 1963, Ser. No. 73,565

Term of patent 7 years

(Cl. D15—1)

FIG.1

FIG.2

FIG.3

FIG.4

FIG.5

FIG.6

FIG.7

FIGURE 1 is a front perspective view of our molded rocking seat with the seat extending upwardly to the left and the back extending upwardly to the right;

FIGURE 2 is a side elevational view of our rocking seat with the back extending upwardly to the left and the seat extending upwardly to the right;

FIGURE 3 is a top plan view of the seat as positioned in FIGURE 2;

FIGURE 4 is a bottom plan view of the seat as positioned in FIGURE 2;

FIGURE 5 is a front elevational view of the seat as shown in FIGURE 2 showing the underside of the seat at the right side of FIGURE 2;

FIGURE 6 is a rear elevational view of the seat as shown in FIGURE 2 showing the underside of the back at the left side of FIGURE 2; and

FIGURE 7 is a cross-sectional view taken along line 7-7 of FIGURE 3.

We claim:

The ornamental design for a rocking seat, as shown.
